POWER LAWN MOWER

James B. Stewart, Glen Ellyn, Ill., assignor to Sunbeam
Corporation, Chicago, Ill., a corporation of Illinois

Filed July 5, 1966, Ser. No. 2,936

Term of patent 14 years

(Cl. D40—1)

Fig. 2

Fig. 3

FIG. 1 is a perspective view of a power lawn mower embodying my new design;

FIG. 2 is a top plan view thereof;

FIG. 3 is an elevation as seen from the right of FIGURE 2;

FIG. 4 is an elevation as seen from the front of FIGURE 2;

FIG. 5 is an elevation as seen from the rear of FIGURE 2; and

FIG. 6 is an elevation as seen from the left of FIGURE 2.

The dominant features of my design reside in the portions shown in full lines.

The lawn mower handle has been omitted from FIGURES 2, 3, 4, 5, and 6 for ease of illustration only.

I claim:

The ornamental design for a power lawn mower, substantially as shown and described.
